US00D565406S

(12) **United States Design Patent** (10) **Patent No.:** **US D565,406 S**
Foskett (45) **Date of Patent:** **** Apr. 1, 2008**

(54) **CAN END**

(75) Inventor: **Peter Stanley Foskett**, Abingdon (GB)

(73) Assignee: **Crown Packaging Technology, Inc.**,
Alsip, IL (US)

(**) Term: **14 Years**

(21) Appl. No.: **29/276,511**

(22) Filed: **Jan. 26, 2007**

(30) **Foreign Application Priority Data**

Jul. 28, 2006 (EM) 000567755-0001

(51) **LOC (8) Cl.** **09-07**

(52) **U.S. Cl.** **D9/438**

(58) **Field of Classification Search** D9/780,
D9/763, 438, 434, 435; 220/906, 273, 269

See application file for complete search history.

(57) **CLAIM**

The ornamental design for a can end, as shown and described.

DESCRIPTION

FIG. 1 is a top perspective view of a can end showing my new design;

FIG. 2 is a bottom perspective view thereof;

FIG. 3 is a top plan view thereof;

FIG. 4 is a bottom plan view thereof;

FIG. 5 is a back side view thereof; and,

FIG. 6 is a right side view thereof.

The lines on the can illustrate shading and contour of the surface.

1 Claim, 5 Drawing Sheets
